UNITED STATES PATENT OFFICE.

MAURICIO REBOLLAR Y PLANCHT, OF HABANA, CUBA.

PNEUMATIC TUBE.

Application filed May 25, 1920, Serial No. 384,105. Renewed February 5, 1923.

To all whom it may concern:

Be it known that I, MAURICIO REBOLLAR Y PLANCHT, a citizen of the Republic of Cuba, and resident of Habana, Cuba, have invented 5 certain new and useful Improvements in Pneumatic Tubes, of which the following is a complete, full, and clear specification.

This invention relates to pneumatic tubes used in combination with resilient tires for 10 automobile wheels and its main object is to provide these tubes at the inside thereof with an attachment which permits to maintain constantly therein the previously regulated inner fluid pressure, by feeding the 15 air that might be required for completing the pressure within the pneumatic tube or either by expelling out such air causing a higher pressure therein than a predetermined pressure, thus preventing a reheating 20 of the tube. An advantage of the invention lies in the fact that the operation of the attachment is effected automatically and the latter is of such special construction that renders impossible the going out of operation thereof. A further object is that notwithstanding the efficient operation of such construction, same is very simple.

The invention is described with reference to the figures of the annexed drawings, in 25 which:

Fig. 1 is a vertical cross section of an inner tube provided with the improvement forming the subject-matter of this invention shown in side elevation.

Fig. 2 is an enlarged vertical section on line 2—2 of Fig. 1.

Fig. 3 is a longitudinal vertical section of the inner tube showing the attachment partially broken.

Fig. 4 is a detail in vertical section on a perpendicular plane with that of section of Fig. 2.

Fig. 5 is a detail in vertical section similar to that of Fig. 4, showing a modified position of the valves.

Fig. 6 is a horizontal section on line 6—6 of Fig. 2.

Fig. 7 is a horizontal section on line 7—7 of Fig. 2.

Fig. 8 is a horizontal section on line 8—8 of Fig. 2.

Fig. 9 is a horizontal section on line 9—9 of Fig. 2.

Fig. 10 is a horizontal section on line 10—10 of Fig. 2.

Fig. 11 is a horizontal section on line 11—11 of Fig. 2.

Fig. 12 is an upper plan view of a form of spring used inside the attachment.

Fig. 13 is an upper plan view of a modified form of said spring.

In these figures 1 illustrates the main body of a pressure air casing of double concentric wall in the shape of a pear and made of a flexible material such as rubber and fabric and composed of four sections integrally connected together, to wit: a lower section 2 in the form of an inverted cone, a short cylindrical zone 3, a higher section of trunk cone shaped 4 whose vertex is united with the lower vertex of an upper section 5 of inverted cone shape, the latter terminating in a peripheral bevel cut 6 and the upper plane wall 6'. Each section comprises two spaced concentric walls 7 and 7' constituting 65 an annular chamber 8 which extends through the sections 2, 3, 4 and the annular chamber 9 in the upper section 5, the chamber 9 being preferably of a thickness which is somewhat less than chamber 8. In this chamber 8 is lodged the helical spring 10 which terminates at the neck 11 where the trunk cone 4 is united with the upper section 5 and in chamber 9 is lodged another spring 12 of less thickness. Said air chamber is 70 placed in radial position inside the pneumatic tube 13 generally used in the tires of vehicle wheels. The lower end or vertex of cone 2 is flat so as to be adapted to the inner face of the pneumatic tube 13 through 75 the intermediate of the rubber re-inforcement 14 and is secured thereto by means of the rivet 15 interiorly ending in a flat head or disc 15'. Inside the inner chamber 17 of the air casing 1 projects downwardly in a 80 hanging manner from the union point between the cone sections 5 and 4, the pipe 16 which is open above and below and terminates near the upper face of disc 15' and which communicates the chamber 17 with 85 the chamber 17' inside the upper section 5, and is provided near its lower end with holes 16' for letting out the air from the first to the second chamber in the event of there 90 being deposited at the bottom of the first one liquids derived from the condensation of the moisture of the air or dust penetrating with the outer air and which are the ones that first are expelled through pipe 16, the 95 main object of this pipe being the extrac- 100

105

110

tion of such liquid or dry residues. Through a central opening in the upper wall 6 of the air casing there is mounted the lower end of a cylindrical valve-bearing metallic member 19 outerly threaded throughout its length and which is widened lowerly forming a peripheral flange 20 which bears against the inner face of the upper wall 6' and being closely fitted to said rim by means of the nut 21 and the washer 23 thereinbetween. This valve-bearing member 19 is hollow inside so as to constitute a cylindrical central valve case 23 in whose wall and at its lower end there are the diametrically opposite vertical recesses 24 inside of which slide the lugs 25 fixed at the top of valve 26 formed by a cylindrical body terminated at its bottom in trunk cone shape and which is extended downwardly for constituting a stem 27 which 10 enters in a hollow cylinder 28 terminated in the conical head 30 which is mounted on the inner face of the inner wall of the upper section 5. The valve 26 is connected at its top to the upper end of a helical spring 31 connected at its top end to the obturating valve 32 which slides within the tubular hole 33 arranged in vertical alinement with the valve case 23 and being an extension thereof, but of minor section, serving as seat to this 15 upper valve the beveled edge of opening 32' in the partition 32'' in continuation whereof and on the same alinement there is the vertical central hole 33'. In a direction from above to below of the member 19 there are 20 four tubular vertical holes 34, 35, 36 and 37 diametrically arranged in pairs, and of which the 34, 35 and 36 ones constitute valve cases, there being located in holes 34 and 36 the valves 38 and 39 which are set on the 25 shoulders 40 and 41 formed by the lower extensions of less width 34' and 36' of said holes 34 and 36 and which communicate through hollow transverse branches 42 and 43 with the central valve case 23. Valves 38 and 39 are securely pending from the helical springs 44 and 45 connected at their upper straight end to a plane cover or disc 46 constituting a safe valve closing the four holes 34, 35, 36 and 37 and which is fitted around 30 a pipe 47 whose lower end screws inside the upper end of central hole 33' of member 19 and accordingly in communication with the conduit 33. From the upper face of said cover or disc 46 projects upwardly conical 35 heels 49 on which bear another upper disc 50 which is also fitted around pipe 47 and on said disc 50 rests a helical spring 51 coiled around the pipe 47, said spring bearing at its upper end against the lower face of the 40 grooved border nut 52 threaded on the upper end of pipe 47, the latter being provided at its upper free end with a sieve 47'. Uppery closed by the cover 46 there is provided at the top of member 19 a beveled annular recess 53 which communicates the four vertical holes 34, 35, 36 and 37. 54 designates a cylindrical shell terminated in an upper spherical casket 55 and which is outerly threaded on the upper end of member 19, this shell being provided with side openings 56 and 56' at different heights and is divided inside in two compartments, an upper aspirating one and a lower expulsating one by the horizontal partition 57 and located between the two series of openings 56 and 56' and through which passes the pipe 47 with the spring 51 coiled thereon. The holes 35 and 37 are continued in sections 35' and 37' of less width which are connected at their lower ends through the transverse holes 59 and 60 with the nipples of widened ends 61 and 62 wherein are fitted the ends of the hoses 63 and 64 made of rubber and canvas or any other similar material and which are terminated in widened mouths 63' and 64' 70 directed towards opposite sides of the pneumatic tube 13 in the longitudinal direction of the latter. In hole 35 there is provided a beveled valve 58 which rests on the shoulder 58' formed by the lower hole extension 35' and which valve pends from the spring 58'' united at its upper straight end to the cover 46. The member 19 is secured to the wall of the pneumatic tube 13 by means of the beveled border nut 65 which is threaded on the lower portion of the former inside the tube 13, the upper face of this nut being in contact with the inner face of the tube wall and by means of the nut 66 threaded also on said member at the outside of tube 13 and pressing this with the intermediate of the metallic bell 67 adapted to the upper neck 68 of the tube. Finally 69 designates a screw which acts as a stop cock through an opening 70 communicating the hole 33 with the exterior and 71 designates a nut threaded on member 19 and which is intended to hold the same in position through the rim of the wheel to which the pneumatic tube 13 is adapted. As a modification 100 which can be effected in the construction of the attachment described, there is illustrated in Fig. 13 a re-inforcing spring for casing 1 which is formed of concentric loops 72 instead of helical springs, and which are 105 connected together by three double canvas bands 73 which are extended inside and outside of the loops and conforming to the irregularities formed by the various sections of casing 1 in its vertical section and 110 which are sewed up to the loops 72. 115 The operation of a pneumatic tube provided with the improvements forming the subject matter of this invention is as follows: 120 For injecting air into the pneumatic tube 13 the shell 54 is removed and there is connected with the end of the tubular stem 47 the feed pipe of any common type of air injecting pump, whereby the air passes 125 130

through the central hole 33 to hole 23, filling the holes 17' and 17 of the air casing 1 and also passes through the transverse holes 42 and 43 to the longitudinal holes 34 and 36 until coming to the upper recess 53 closed by the cover 46 and from there it passes to the valveless longitudinal hole 37 and through the transverse hole 60 goes to the hose 64, thus feeding with air the interior 10 of the pneumatic tube 13 until obtaining the required pressure which is previously regulated by the tension of spring 51 of the safety valve. Once the vehicle moves forward, if there is the required pneumatic 15 pressure, the air casing 1 will be kept expanded by the same inner pressure of the pneumatic tube aided by the expansion of the inner springs 10 and 12, but when lacking the required pressure in the interior of 20 the pneumatic tube 13 the weight of the vehicle compels the walls of the air casing to flatten down whereby the cylindrical body 28 will ascend closing against the valve 26 and pushing upward the latter and with it 25 the spring 31 and the valve 32 against its seat 32' so that closing the valves 26 and 32 and compressing the air confined in chamber 17' of the upper section 5 of casing 1 when the latter is flattened down, same is 30 compelled to be introduced in the transverse holes 42 and 43 and to pass to the vertical holes 34 and 36 to raise or open the valves 38 and 39 and continues through the holes where said valves slide enters the beveled 35 annular recess 53 and descends through the hole 37 from where it passes to the air injecting hose 64 in the pneumatic chamber 13. Owing to the fact that the spring provided in the upper section 5 of the casing is 40 of less thickness than that of the other sections 2, 3, and 4 of casing 1, said upper section 5 is wholly flattened down, but notwithstanding this, if the lack of pressure of the tube would be exceedingly short, this would 45 result in the whole flattening down of the air casing 1 and the compressed air of the inner chamber 17 would raise the valve 26 from its seat 28 after passing through pipe 16 and the air will be guided towards the 50 holes 34 and 36 in the same manner previously used, and thence through the recess 53 to hole 37 and hose 63, into tube 13.

If for any reason whatsoever the pressure in the pneumatic tube 13 be raised, said 55 pressure will offset the tension of the spring 51 which regulates the safety valve and the inner air raises the cover 46 and escapes out through openings 56 after having passed through the hose 63 and 64 and holes 35 and 37, and having raised the valve 58. The 60 hose 63 which is connected to the valve case 35 does not permit the access of the air to the pneumatic tube 13 but serves only for the expelling out of the air or any other strange 65 body that might be inside the pneumatic

tube, while the hose 64 which is connected to the tubular hole 37 which is not provided with valve, it can either admit or expel the air towards or from the pneumatic tube 13 in the various conditions of the operation. 70 In those cases wherein the pressure in the pneumatic tube be the normal or required one, it will not take place the flattening down of the air casing and in case of such smashing taking place and the attachment 75 operating without necessity, the valves should be open themselves thus letting out the air. It is quite desirable to insert a piece of cotton in the inner end of the shell 54 with the aim in view of preventing the 80 entrance of dust and maintaining nevertheless the required circulation of air through said holes between the apparatus and the atmospheric air.

It is obvious that many changes can be 85 made in the described improvement as well as adapting my invention to all the purposes to which its construction might serve, whereby I do not limit myself to what has been described, but desire that the Letters- 90 Patent may cover all that which is within the scope of the appended claims.

What I claim is:

1. In pneumatic tubes, a fluid collapsible closed supplemental container arranged in 95 a pneumatic tube, a fluid feeding member from the exterior which is connected to said supplemental fluid container and which passes through the wall of the pneumatic tube, said member being provided with a 100 central longitudinal bore to which is connected a pressure fluid feeding tube and which hole serves as seat for valves connected through a helical spring, one of said valves being arranged to open inwardly and 105 the other being arranged to slide in an enlarged extension of said bore in combination with a seat formed at the interior of the supplemental fluid container, said member having also four longitudinal holes arranged crosswise around the central bore and terminating short of the inner end of 110 said member, two of said holes communicate with the extension of the central bore and being provided with valves which open from inwardly, and one of the holes having an outwardly opening valve, the last two mentioned holes communicating below the level of said valve with the interior of the pneumatic tube, and the four 115 longitudinal holes being united at the top of said member by a continuous recess a spring pressed cover closing this recess said cover acting as a safety valve.

2. In pneumatic tubes, a fluid collapsible 125 closed container arranged in the interior of the pneumatic tube and whose inner cavity is divided in two compartments, an upper one of less volume and a lower one of much larger volume which are in com- 130

munication with each other through a pipe which leads from the former one till near the lower part of the second, the inlet of the upper compartment being in connection with the fluid feeding member of the pneumatic tube, and valves in the compartment of less volume and in the fluid feeding member so that when the fluid pressure is reduced in the interior of the pneumatic tube there be contracted first and in a higher degree the compartment of less volume than that of the larger volume to compel the inner fluid of the former thereby compressed to supply the pneumatic tube thus reinstating its pressure and the contraction of the compartment of larger volume acting thereafter for supplying more fluid to the pneumatic tube if required.

3. In pneumatic tubes, a supplemental closed fluid container, collapsible through the flattening down of its walls and arranged in the pneumatic tube and whose inner cavity is divided in two compartments, an upper one of less volume and whose walls yields in less degree than the walls of the lower compartment which is of larger volume, both compartments being in communication with one another through a tube which leads from the former towards near the bottom of the second one, a cylindrical fluid feeding member from the exterior which is connected with the upper compartment of the supplemental fluid container and passes through the wall of the pneumatic chamber, said member being provided with a central longitudinal hole connected to a pressure fluid feeding tube from the exterior and which hole serves as lodging for two opposite valves connected through a helical spring and of which one opens inwardly and the other one loosely slides through suitable guides inside an extension of said central hole, in combination with a seat formed in a cylinder connected to the bottom of the upper compartment of the supplemental fluid container directly above the tube communicating both compartments, said member being also provided with four longitudinal holes arranged cross-wise around the central hole and terminating short of the inner end of the said member, two of said holes communicating with the extension of the central hole and being provided with valves which open inwardly one of the other two holes having a valve which opens inwardly, these last two mentioned holes communicating beneath the level of said valve with nozzleled rubber tubes leading from in the interior of the pneumatic tube in opposite directions, and the four longitudinal holes being united at the top of the said member by an annular recess, a disc cover closing this recess and which is tightened by the tension of a spring coiled on the pressure fluid feeding tube and whose tension is regulated by a nut screwed on said tube, said cover acting as a safety valve.

In witness whereof I affix my signature,
MAURICIO REBOLLAR y PLANCHT.
